UNITED STATES PATENT OFFICE.

ERNEST KOHLER, OF ALAMEDA, CALIFORNIA.

GAME.

1,186,801.

Specification of Letters Patent. Patented June 13, 1916.

Application filed November 1, 1915. Serial No. 59,024.

To all whom it may concern:

Be it known that I, ERNEST KOHLER, a citizen of the United States, residing at Alameda, in the county of Alameda and State 5 of California, have invented certain new and useful Improvements in Games, of which the following is a specification.

This invention relates to improvements in games, the principal object being to provide 10 a game, which may be played in a number of ways, which may be used also as a puzzle, and for the same purpose that disks are used.

With these and other objects in view my 15 invention consists in the novel construction, and arrangement of parts herein illustrated and more specifically pointed out in the appended claims.

Reference being had to the accompanying 20 drawing forming a part of this specification, Figure 1 is a view in plan of my improved game. Fig. 2 is a view in side elevation. Fig. 3 is a view in section on the line 3—3, Fig. 1.

25 Denoting corresponding parts in the several views by the same numerals of reference, the game consists of the body 1 having the circular end 2, and the rectangular portion 3, which is continued in the handle 4. 30 The portions 2 and 3 have a continuous hollow cavity 5, which is provided with a cover plate 6 having the outlines of these portions and having a glass window 7 over the portion 3. The body is provided with a pair 35 of legs 8 of equal length and a third leg 9 somewhat shorter than the other two. These legs are arranged in triangular relation and legs 8 are disposed at right angles to the center line of the body so that in this 40 manner the game may rest on these legs and be tilted back and forth and tilted thereon.

Within the rectangular portion 3 are a number of division walls 10, substantially the length of the square portion 3 and extending upwardly to a point adjacent the glass cover thus providing runways in which certain balls 11 are to be placed. In one of the side walls of the rectangular portion 3 is provided a slot 12, the use of which is 50 hereinafter described.

Having thus described the construction of my apparatus, several ways in which it may be used are as follows:—If the game is to be used as a puzzle an endeavor is made to 55 place the balls, which are normally in the cavity 5, in the spaces between the division

walls 10 in some regular order. These balls are provided in three colors and the endeavor would be to place the balls in three rows, each row having a separate color. Or, 60 some other order may be adapted as, for instance, placing all balls of one color in one slot and all others of another color in the next and the third color in a third slot. This makes an exceedingly difficult puzzle owing 65 to the closed condition of the box and one in which it is hard to cheat.

If the game is to be used in scoring points the preferable method of using it is to tilt it forward until all the balls run down in 70 the recess 5 and then tilt it backward allowing all the balls to flow into the various slots as they will. Then all balls of the same color, which lie adjacent each other in a vertical or horizontal row, are 75 counted as one point; thus if three red balls lie adjacent each other in a row and three white ones in another row, then six points would be scored. As illustrated in Fig. 1, it would be the highest possible 80 number of points, which is 15. In using the game in this manner both balls in the horizontal and vertical rows count so long as there are three or more in one row and they are adjacent each other. 85

Another method of playing the game is to remove the cover plate 6 and all the balls except one. This ball is placed in the first slot and the small implement inserted through the opening 12 just back of the ball. 90 This implement is then given a sharp upward blow causing the ball to fly to the outer end of the circular recess and fall into one of the other slots. These slots are numbered, as shown in 13, and the slot in which the ball falls scores that many points. Using the game in this manner the device rests on the three legs so that the ball always tends to roll down into one of the slots between the division walls 10. 95

It will thus be apparent that I have provided a game board having a variety of uses, which is novel and useful in its application, and while I have shown the preferred embodiment of my invention it will be understood that minor changes may be made in detail and design without departing from the scope of the claims. 100

I claim as new and wish to cover by Letters Patent:—

110 1. A game apparatus comprising a circular end, a rectangular portion formed on said

- 5 circular end, said end and rectangular portion having a common recess formed concentric with the outlines thereof, a cover plate for said recess, a plurality of division walls in the recess within said rectangular portion forming runways extending the length of said rectangular portion, and a plurality of spheres adapted to be placed in said runways.
- 10 2. A game apparatus comprising a circular portion, a rectangular portion of lesser width formed on said rectangular portion,

said portions having a common recess concentric with the outlines thereof, a cover plate for said recess, a plurality of division walls in the recess within said rectangular portion forming runways, a plurality of various colored balls adapted to be placed in said runways, a handle formed on said rectangular portion and legs attached to the under side of circular portion adjacent its junction with said rectangular portion.

In testimony whereof I affix my signature.
ERNEST KOHLER.

Copies of this patent may be obtained for five cents each, by addressing the "Commissioner of Patents, Washington, D.C."
